BUILDING STRUCTURE

Frank E. McCabe, Shaker Heights, Ohio, assignor to The Grabler Manufacturing Company, Cleveland, Ohio, a corporation of Ohio

Application June 1, 1935, Serial No. 24,523

10 Claims. (Cl. 189—85)

This invention relates to building structures, and more particularly to face-work building structures, and has for an object the provision of new and improved structures of this character.

In the drawing accompanying this specification and forming a part of this application, I have shown, for purposes of illustration, embodiments which my invention may assume, and in the drawing:

10 Figure 1 is a fragmentary perspective view of a building structure, embodying the invention, disclosing parts of the same in horizontal section, and disclosing parts broken away to more clearly illustrate the construction,

15 Figure 2 is an enlarged fragmentary horizontal sectional view, corresponding substantially to the line 2—2 of Figure 1,

Figure 3 is a view similar to Figure 2, corresponding substantially to the line 3—3 of Figure 1,

20 Figure 4 is an enlarged fragmentary horizontal sectional view, corresponding substantially to the line 4—4 of Figure 1,

25 Figure 5 is a fragmentary perspective view, similar to Figure 1, and disclosing a different embodiment of the invention, while

Figure 6 is an enlarged horizontal sectional view, corresponding substantially to the line 6—6 of Figure 5.

As shown in Figures 1 through 4 of the drawing, the invention comprises a building structure, wherein a plurality of facing panels 10 are disposed edge to edge and flatwise along the surface of a supporting wall 11, which may be the front wall of a building or the like, and the panels 10 are secured in position along said wall by a plurality of sets of securing means, each set being indicated generally by the reference character 12, and adapted to be positioned between juxtaposed edges of each pair of panels 10; the sets 12 are duplicates in construction and operation and only one of the same will be described in detail.

Each of the sets 12 comprises an elongated member 13, preferably of sheet metal, and channel-shaped in cross-section, having an intermediate portion 14, integrally formed outwardly extending webs 15, merging with inturned overhanging flanges 16, spaced apart to define a continuous slot 17, through which marginal portions of the panels 10 may be inserted. The intermediate portion 14 of the member 13 is adapted to rest flat against the face of the supporting wall 11, and at intervals along its length is provided with slots 18, each elongated in the direction of the length of the member 13. Associated with each of the slots 18 is an anchoring member 19,

comprising a screw-bolt 20, extending through the slot 18, having a head 21 bearing against the outer face of the intermediate portion 14, and a shank threaded into a wedge part 22, and the wedge part 22 is encased in an expandable sleeve 23, which may be of lead. The wedge part 22 and sleeve 23 may be accommodated in a suitable cavity 24 formed in the supporting wall 11, and rotation of the bolt 20 serves to draw the wedge part 22 inwardly and to expand the sleeve 23 into anchoring engagement with the wall of the cavity 24. When all of the anchoring members 19 have been tightened, the member 13 is fixedly secured to the supporting wall 11, and the slots 18 permit necessary movement incident to expansion and contraction under varying conditions.

Cooperating with each of the fixed members 13 is a plurality of clamping members 25, each preferably in the form of an oblong piece of metal sufficiently long so that when the same is within the channel-shaped formation of the member 13 it will not turn lengthwise thereof, said clamping members 25 being adapted to be inserted through transverse slots 26 in the flanges 16 of the member 13, and when in position presenting engaging portions 27 and 28 adapted to cooperate with the inner surfaces 29 of the overhanging flanges 16, to provide clamping means within the channel-shaped formation of the member 13. Each of the clamping members 25 has threaded therethrough an actuating screw 30 adapted at its inner end to bear upon the inner surface of the intermediate portion 14 and, when adjusted, operating to force the engaging portions 27 and 28 of the clamping member 25 toward the inner surfaces 29 of the overhanging flanges 16, each screw 30 having a kerfed head 31 for accommodation of a tool by means of which the screw 30 may be adjusted.

Each of the sets of securing means 12 is adapted to secure juxtaposed edges of a pair of the panels 10 to the supporting wall 11. The panels 10 are formed for cooperation with the securing means 12, each of the panels 10 comprising a channel-shaped formation having an intermediate portion 32, an angularly extending web 33 along one edge of the portion 32, and an angularly extending web 34 along the opposite edge of the portion 32, and the web 33 has an inturned marginal flange 35 adapted to be clamped between the clamping surface of the engaging portion 27 of the clamping member 25 and one of the inner surfaces 29 of the adjacent flange 16, while the web 34 has an inturned marginal flange 36 adapted to

be clamped between the engaging portion 28 and adjacent the inner surface 29 of the flange 16.

Installation of the face-work structure is preferably effected by first securing a plurality of the members 13 vertically and in spaced relation along the supporting wall 11, through the medium of the anchoring members 19, the members 13 being spaced apart a distance corresponding to the width of the panels it is desired 5 to use. The clamping members 25 are then inserted at intervals along the length of the member 13 through the slots 26; the marginal flanges 35 and 36 of adjacent panels 10 are then inserted through the slot 17 into the interior of the 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 channel-shaped formation of the related member 17, and the screws 30 are then adjusted to clamp the marginal flanges 35 and 36 in position. After all of the clamping members 25 have been adjusted, the space between the webs 33 and 34 of the secured panels 10, may be filled with a suitable filling material, indicated at 37, the heads of the screws 30 and of the anchoring members 19 providing key means therefor, and in turn being held against accidental loosening by 5 said filling material. Although the securing members 13 are shown and described as secured vertically along the supporting wall 11, it will be understood that these members may be disposed horizontally, and the panels 10 secured thereto, or, if desired, the securing members 13 may be arranged both vertically and horizontally to present rectangular formations to which all four edges of the panels 10 may be secured, the panels 10 in this latter case of course having all 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 four edges formed as heretofore described to cooperate with the securing means.

Referring to Figures 5 and 6, a somewhat different embodiment of the invention is disclosed, comprising elongated securing members 38, each 40 having an intermediate portion 39 and outwardly converging flanges 40 and 41, the intermediate portion 39 being secured at intervals to the supporting wall 42 by anchoring members (not shown) identical to the anchoring members 19 heretofore described. A plurality of wedge-shaped clamping members 43 are provided for operation within the flanges 40 and 41, each comprising an intermediate portion 44 through which an actuating screw 45 extends, and having wings 46 and 47 adapted to cooperate with the flanges 40 and 41, respectively, to form clamping means. Panels 48 and 49 are provided, each having an intermediate portion 50 and inwardly inclined flanges 51 and 52, the flange 51 of the panel 48 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 being adapted to be wedged and clamped between the flange 40 and wing 46 and the flange 52 of the panel 49 being adapted to be wedged and clamped between the flange 41 and wing 47, when the screw 45 is rotated, the inner end 60 of the screw 45 bearing upon the inner surface of the intermediate portion 39 and forcing the clamping member 43 outwardly to effect this action.

This construction may be assembled by inserting the flanges 51 and 52 of the panels 48 and 49 within the flanges 40 and 41, and then inserting the clamping members 43 from the end of the member 38, but preferably the clamping members 43 are inserted through slots 53 in the flanges 40 and 41, then shifted and partially adjusted, and the flanges 51 and 52 of the panels 48 and 49 may then be inserted between the flanges 40 and 41 of the member 38 and the wings 46 and 47, respectively, of the clamping members 43, and the screws 45 screwed home.

After the panels 48 and 49 are in position, suitable filling material, indicated at 54, is employed to fill the cracks between the adjoining edges of the panels, and by reason of the undercut formation of the cracks, key means are provided for the filling material, the heads of the screws 45 and of the anchoring members also providing key means, and in turn held by the filling material against accidental loosening.

It will be apparent to those skilled in the art 10 that I have accomplished at least the principal object of my invention, and it also will be apparent to those skilled in the art that the embodiments herein described may be variously changed and modified, without departing from 15 the spirit of the invention, and that the invention is capable of uses and has advantages not herein specifically described; hence it will be appreciated that the herein disclosed embodiments are illustrative only, and that my invention 20 is not limited thereto.

I claim:

1. A building structure of the character described, comprising: a support; a facing member having projecting means thereon; a device for 25 securing said facing member to said support, said device including means fixed to said support and having inclined outwardly converging flanges adapted to receive the projecting means of said facing member therebetween; and means arranged within said flanges and engageable with said projecting means to wedge the same forwardly into clamping engagement with said converging flanges.

2. A building structure of the character described, comprising: a support; a facing member having projecting means thereon; a device for securing said facing member to said support, said device including means fixed to said support and having inclined outwardly converging flanges 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 adapted to receive the projecting means of said facing member therebetween; and holding means arranged within said flanges and engageable with said projecting means to wedge the same forwardly into clamping engagement with said converging flanges; said converging flanges having slotted openings to facilitate insertion of said holding means within said flanges.

3. A building structure of the character described, comprising: a support; juxtaposed facing members having projecting means thereon; a device for securing said facing members to said support, said device including means fixed to said support and having inclined outwardly converging flanges adapted to receive the projecting means of said facing members therebetween; and means arranged within said flanges and engageable with said projecting means to wedge the same forwardly into clamping engagement with said converging flanges.

4. A building structure of the character described, comprising: a support; juxtaposed facing members having projecting means thereon; a device for securing said facing members to said support, said device including means fixed to said support and having inclined outwardly converging flanges adapted to receive the projecting means of said facing members therebetween, and said projecting means conforming to the contour of said converging flanges; means arranged within said flanges and engageable with said projecting means to wedge the same forwardly into clamping engagement with said converging flanges; and filling means, filling the space between the projecting means of said facing mem- 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500

bers, and keyed by the undercut disposition thereof.

5. A building structure of the character described, comprising: a support; a facing member having projecting means thereon; a device for securing said facing member to said support, said device including a securing member fixed to said support, channel-shaped in cross-section, and having overhanging flanges, said projecting 10 means of said facing member being adapted to be inserted within the space bounded by said flanges; and clamping means disposed within the channel-shaped securing member, interposed between the base of the latter and the inserted projecting means, bearing upon said base, and constructed and arranged to be spread and thereby clamp said projecting means against the under 15 surface of at least one of said overhanging flanges.

20. 6. A building structure of the character described, comprising: a support; a pair of facing members, each having projecting means thereon; a device for securing said facing members to said support, said device including a securing member fixed to said support, channel-shaped in cross-section, and having overhanging flanges, beneath each of which the projecting means of one of said facing members is adapted to be inserted; and a single clamping means disposed 25 within the channel-shaped securing member, interposed between the base of the latter and the inserted projecting means, bearing upon said base, and constructed and arranged to be spread and thereby engage and clamp the projecting means 30 of each of said facing members against the under surface of one of said overhanging flanges.

7. A building structure comprising: a facing member; supporting means, including housing means having an outwardly extending inclined 40 overhanging wedge surface; and spreadable wedge means disposed within said housing, adapted to spread and to cooperate with said wedge surface, and constructed and arranged when spread to move outwardly, and remaining to 45 clamp said facing means in position with respect to said housing.

8. A building structure comprising: a facing member; supporting means, including a device having outwardly extending, spaced converging 50 means, one of which has a wedge surface; and spreadable wedge means disposed between said

converging means, constructed and arranged to be spread and when spread to move outwardly, said wedge means also being shiftable as a unit with respect to said device until spread, and remaining when spread to clamp said facing member to said device. 5

9. A device for securing a facing member to a support, said device including a first wall having a portion presenting a continuous surface, adapted to be secured to said support, and a spaced 10 wall connected with, and overhanging the continuous surface portion of said first wall, said spaced wall being adapted to receive there beneath projecting means of said facing member; and holding means interposed between the continuous surface portion of said first wall and said inserted projecting means, and bearing upon said continuous surface, said holding means being shiftable as a unit to any position with reference 15 to the continuous surface of said first wall, and constructed and arranged to be elongated between said continuous surface and said projecting means and thereby to clamp the latter in position, said holding means including means projecting exteriorly of said overhanging spaced 20 wall, and accessible for manipulation to loosen or tighten said holding means.

10. A building structure comprising: a facing member having projecting means thereon; supporting means, including a device secured to said 30 supporting means and having outwardly spaced means beneath which the projecting means on said facing member is adapted to be disposed, said supporting means having a portion lying beneath said outwardly spaced means presenting 35 a continuous surface; and spreadable clamping means interposed between the continuous surface of said supporting means and said projecting means, and bearing against said continuous surface, and constructed and arranged to be spread, 40 and thereby to clamp said projecting means in position against the under surface of said outwardly spaced means, said spreadable clamping means when loosened, being shiftable as a unit along said continuous surface, and reengageable 45 at any point therealong, said clamping means extending outwardly beyond said outwardly spaced means to present means exteriorly accessible by which said clamping means may be manipulated. 50

FRANK E. McCABE.
